CLAIM

The ornamental design for a corner bead roller tool, as shown and described.

DESCRIPTION

FIG. 1 is a left side, top, rear perspective view of the corner bead roller tool embodying the design according to a first aspect, with a mount thereof, fasteners thereof, and a pole thereof shown in stippled lines and not forming part of the design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof;

FIG. 7 is a front elevation view thereof;

FIG. 8 is a left side, top, rear perspective view of the corner bead roller tool embodying the design according to a second aspect, with a mount thereof, fasteners thereof, and a pole thereof shown in stippled lines and not forming part of the design;

FIG. 9 is a left side elevation view thereof;

FIG. 10 is a right side elevation view thereof;

FIG. 11 is a top plan view thereof;

FIG. 12 is a bottom plan view thereof;

FIG. 13 is a rear elevation view thereof; and,

FIG. 14 is a front elevation view thereof.
